195,500

COMBINED OUTDOOR RECREATIONAL PAVILION, BARBECUE GRILL, AND PATIO

John W. Munn, P.O. Box 2144, and Allen D. McKenzie,
Box 13, both of Casper, Wyo.

Filed Mar. 5, 1962, Ser. No. 69,073

Term of patent 3½ years

(Cl. D13—1)

We claim:

The ornamental design for a combined outdoor recreational pavilion, barbecue grill, and patio, as shown.
